UNITED STATES PATENT OFFICE.

ADDISON V. SANFORD, OF ELMIRA, ASSIGNOR TO FREDERICK DIETZ, OF NEW YORK, AND S. W. COUVIN, OF MIDDLETOWN, NEW YORK.

BLACKING-BOX.

SPECIFICATION forming part of Letters Patent No. 295,677, dated March 25, 1884.

Application filed November 9, 1883. (No model.)

To all whom it may concern:

Be it known that I, ADDISON V. SANFORD, of Elmira, in the county of Chemung and State of New York, have invented certain new and useful Improvements in Blacking-Boxes, of which the following is a full, clear, and exact description, reference being had to the accompanying drawings, and to the letters of reference marked thereon.

10 My invention relates especially to boxes used for containing shoe polish or blacking, and has for its object the provision of a device simple and cheap to construct, and wherein means are employed for holding the box by a handle and 15 raising or lowering the cover without soiling the fingers.

My invention consists, essentially, in a box constructed of sheet metal and provided with a cover of the same material; a handle, made 20 of a single piece of wire having bends therein, is arranged to engage with the ends of a wire cover-holder, also made in a single piece, and having a projecting thumb-piece for raising the cover or lid; and my invention also involves certain other novel and useful combinations or arrangements of parts and peculiarities of construction and operation, all of 25 which will be hereinafter first fully described, and then pointed out in the claim.

30 In the drawings, Figure 1 is a plan view of my improved blacking-box, and Fig. 2 is a side elevation thereof. Fig. 3 is a vertical sectional view at line x x of Fig. 1. Fig. 4 shows the improved box as provided with a 35 set-screw and having an ordinary blacking-box secured therein.

Like letters of reference, wherever they occur, indicate corresponding parts in all the figures.

40 The special advantages of my box will be readily understood. The box may be securely

held in the hand, and the cover raised therefrom or returned thereto by a simple movement of the thumb, all danger of soiling the hands is overcome, and no trouble will be experienced in always keeping the blacking securely covered against drying out and gathering dirt. The box may be made of any approved size, and blacking placed directly therein; or large sizes may be employed, the cover 5 being removed from the ordinary box, the box being placed in my improved box and securely held against movement by a set-screw or equivalent mechanism.

A is the box, made of sheet metal in any 5 approved manner. B is a handle, constructed of a single piece of wire and secured to the box, as shown. At b the wire of the handle is doubled over upon each side, forming sockets, into which the extremities of the hinge-wire 6 C extend, wire C being affixed to the cover D and provided with a thumb-piece, E.

Fig. 4 shows a box constructed in accordance with my invention, and provided with a set-screw, F, adapted and arranged to hold an 6 ordinary blacking-box, G, securely in place, the cover thereof being removed.

Having now fully described my invention, what I claim as new therein, and desire to secure by Letters Patent, is—

The box A, cover D, handle B, having bends b therein, and cover-holder C, having ends b' and bearing thumb-piece E, the whole combined and arranged to operate substantially as shown and described.

In testimony that I claim the foregoing I have hereunto set my hand in the presence of two witnesses.

ADDISON V. SANFORD.

Witnesses:

C. E. VINTON,
WM. T. POST.

Correction in Letters Patent No. 295,677.

It is hereby certified that in Letters Patent No. 295,677, granted March 25, 1884, upon the application of Addison V. Sanford, of Elmira, New York, for an improvement in "Blacking Boxes," the name of one of the assignees of said Letters Patent was erroneously written and printed "S. W. Couvin," instead of *S. W. Corwin*; and that the proper correction has been made in the files and records pertaining to the case in the Patent Office, and should be read in the patent to make it conform thereto.

Signed, countersigned, and sealed this 1st day of April, A. D. 1884.

[SEAL.]

M. L. JOSLYN,
Acting Secretary of the Interior.

Countersigned:

BENJ. BUTTERWORTH,
Commissioner of Patents.
